VENETIAN BLIND

Robert H. Swackhamer, Oakland, Calif.

Application April 21, 1948, Serial No. 22,411

11 Claims. (Cl. 160—34)

1

My present invention relates to Venetian blinds or the like.

While Venetian blinds of the type now in use have many satisfactory features they also have many disadvantages. Among such may be noted such factors as that their appearance is marred by the exposed slat supporting tapes, that they are difficult to clean, and that when not in use, they detract from the appearance of the windows.

In accordance with my invention, I provide a pair of members mounted adjacent the sides of the window casing for vertical movement. Each member has a plurality of pockets opening in the same direction transversely of its direction of travel with corresponding pockets of each member being adapted to receive the spindles of a slat. Associated with the members are guide means slidably guiding the spindles when supported by a pair of pockets and adjacent the upper part of the casing are means to enable the spindles to be transferred into or out of the pockets above the guide means.

In practice, the members are a pair of spring wound bands each of which extends downwardly into housing units attached to one side of the casing. The housing units have transversely aligned mouths adjacent their upper ends in their exposed faces towards which the pockets of the bands are disposed, transversely aligned vertical slots in their opposed faces which are intersected by the band pockets, and transversely aligned downwardly and inwardly inclined slots interconnecting the mouths and the vertical slots. A transverse member slidably guided by the vertical slots is connected to the ends of the bands to maintain each pocket of one band transversely aligned with a pocket of the other band. By this construction, the spindles of a slat may enter a pair of transversely aligned pockets when presented at the mouths of the units and be transferred into the pockets and into the vertical slots of the unit as the bands move downwardly or the spindles of a slat may be transferred from their vertical path established by the vertical slots outwardly and upwardly through the mouths of the units as the bands are raised.

In practice, I provide a magazine for the slats which includes a pair of channels to support the extremities of the spindles of each slat and the channels extend downwardly and outwardly to enter the mouths of the units and to intersect the path of the spindles at the junction of the vertical and downwardly and inwardly inclined slots of the housing units so that as the bands move downwardly, slats move downwardly under the

2

influence of gravity with each entering a pair of pockets when exposed at the mouths of the units and being transferred into the vertical slots to complete the blind. As the transverse member is raised, the spindles of the slats are successively engaged by the extremities of the channels and are transferred into the magazine. The slats may be locked therein and the magazine detached from the casing when the slats are to be removed for cleansing or other service.

I also provide means to tilt the slats from a normal position and to accomplish this result, I employ a third spring wound band having a plurality of spaced pockets opening towards the mouth of the unit in which it is housed. This band, while movable with the other bands, is also movable relative thereto between a first position in which each of the pockets is spaced slightly above a pair of pockets of the other bands and a second position in which each of its pockets is spaced slightly below such a pair of pockets. I provide one spindle of each slat with a crank portion disposed to enter the pocket adjacent the tilting band whereby that slat is tilted in one direction when the tilting band is in its first position and in the opposite direction when the tilting band is in its second position. When any one slat is manually tilted from one direction towards the other position, its crank portion actuates the tilting band to cause a corresponding tilting of the other slats.

By this construction, I am thus able to provide Venetian blinds in which exposed slat carrying tapes are eliminated, in which the slats are compactly stored in a magazine when the blind is raised and in which they are fed therefrom and connected to the bands in properly spaced relation when the blind is lowered thereby to combine attractiveness of appearance with maximum convenience both in use and in service.

In the drawings, I have shown an illustrative embodiment of my invention from which its many novel features and advantages will be readily apparent.

45 In the drawings:

Fig. 1 is a front view of a window, as viewed from the inside, equipped with a Venetian blind in accordance with my invention.

Fig. 2 is a section, on an enlarged scale, along the lines 2—2 of Fig. 1.

Fig. 3 is a perspective view of one of the slats.

Fig. 4 is a front view, on an enlarged scale, of the blind of Fig. 1 with the magazine removed.

Fig. 5 is a section, on an enlarged scale, along the lines 5—5 of Fig. 4.

Fig. 6 is a section, similar to Fig. 2, along the lines 6—6 of Fig. 1.

Fig. 7 is a fragmentary view showing many of the parts of Fig. 6 in perspective.

Fig. 8 is a fragmentary view showing in front view the spring means holding the slats in their tilted position.

Fig. 9 is a diagrammatic view showing the means ensuring the maintenance of the slats in a horizontal position.

Fig. 10 is a perspective view showing the interior of the magazine.

Fig. 11 is a front view of the housing for the slat carrying bands with its cover removed.

Fig. 12 is a section along the lines 12—12 of Fig. 11 with the cover attached.

Fig. 13 is a view similar to Fig. 12 but showing a modification thereof, and

Fig. 14 is a vertical section through the housing for the tilting band.

As illustrative of a window with which a Venetian blind in accordance with my invention is used, I have generally indicated a window casing at 15. Supported adjacent the upper part thereof and interiorly of the window, not shown, is a transverse mount 16 which may or may not be a part of the window casing structure, but is here shown as a separate element.

In the illustrative embodiment of my invention shown in the drawings, I have shown housing units 17 and 18 secured to the sides of the window casing 15. The units 17 and 18 have, respectively, transversely alined vertical slots 19 and 20 in their adjacent faces, transversely alined mouths 21 and 22 in their exposed or inner faces (see Fig. 4), and transversely alined downwardly and inwardly inclined slots 23 (see Figs. 2 and 6), each of which effects communication between the mouth of a housing unit and its vertical slot.

While the housing units may be otherwise formed, the construction detailed in the drawings has proved satisfactory. Except for its upper portion generally indicated at 24 and its cross sectional area, the housing unit 17 is substantially the same in construction as the housing unit 18. As may be most clearly seen in Fig. 5, each housing unit consists of a backing strip 25 anchored to the sides of the window casing 15 by screws 26 extending through the outwardly disposed flanges 27 of the side members 28 which include inturned flanges 29 spaced from each other to provide the vertical slot of that housing unit. Each backing strip 25 has a pair of spaced ribs 30 in parallel with such vertical slots. Secured to each of the side members 28 adjacent its flange 29 is a vertically disposed spacer 31. While the mouth 22 and the downwardly and inwardly inclined slot 23 of the housing unit 18 are formed in its side member 28 and inner flange 29, respectively, the housing unit 17 includes the upper portion 24 which may be most clearly seen in Figs. 6 and 7. It consists of a backing strip 32 and a side member 33 having an outwardly disposed attaching flange 34 and an oppositely bent end 35. The upper portion 24 is spaced from the upper end of the main part of the housing unit 17 to provide the mouth 21 and the adjacent edges of the end 35 and the innermost of the flanges 29 are spaced from each other and shaped to provide the downwardly and inwardly inclined slot 23 of the housing unit 17. Within the upper portion 24, I mount a pair of spacer blocks 36 which are spaced from each other and the end 35 of the side member 33.

As is most clearly shown in Fig. 4, I attach to

the mouth 16 a casing 37 housing a spring wound drum for the flexible bands 38 and 39 which are preferably of metal. The band 38 is trained through a guide bearing 40 and enters the upper portion 24 of the housing unit 17 in the space between one of the spacer blocks 36 and the end wall 35 and extends downwardly into the main part of the housing 17, being there confined between the spacers 31 and the flanges 29 in parallel with the sides of the window casing 15. The band 39 is trained over a pulley 41 and enters the upper end of the housing 18 between its flanges 29 and its ribs 30 and in parallel with the sides of the window casing 15.

The corresponding edge of each of the bands 38 and 39 is formed with a plurality of spaced pockets 42 opening towards the mouths of the housing units and dimensioned so that their closed ends register with the vertical slots of the housing units. The lower corner established by each pocket 42 is rounded. The ends of the bands 38 and 39 are connected to a cross member 43 with each pocket 42 of one band transversely alined with a pocket 42 of the other band.

The cross member 43, as may be most clearly seen in Figs. 7 and 9, consists of a main portion 44, the length of which is substantially equal to the distance between the housing units 17 and 18 and extensions 45 and 46 dimensioned to enter the slots of the housing units. The extensions 45 and 46 terminate in clamps 47 and 48 respectively, and the ends of the bands are apertured as at 49 (see Fig. 9) to receive the extensions thereby to be detachably connected thereto.

By this construction, the bands are wound on the drum or unwound therefrom by raising or lowering the cross member 43 and to ensure that the cross member 43, should it be gripped adjacent one housing unit to raise or lower it, is positively maintained in a horizontal position, I have provided means to equalize its travel.

As may be most clearly seen in Figs. 4 and 9, I have shown a threaded spool 50 rotatably supported on the mount 16. Adjacent the upper end 45 of each of the housing units 17 and 18 is a pair of axially alined pulleys 51 and 52, and within each housing unit and adjacent its lower end, is a pulley 53, preferably located below the lower extremity of the rib 30 adjacent the concealed or outer face of the housing units. An endless cable, generally indicated at 54, is trained over the pulleys 53 to establish reversed loop ends 55 and 56 (see Fig. 9) which establish strands 57 and 58. The strand 57 is trained over the pulley 51 of one pair and the pulley 52 of the other pair and the strand 58 is trained over the other pulley of each pair and has a turn about the spool 50. The clamps 47 and 48 secure the cross member 43 to the strand 57 in the loop 55 and to the strand 58 in the loop 56. By this construction, the transversely alined portions of the cable 54 travel in the same direction when the cross member 43 is raised or lowered and the bands 38 and 39 are moved uniformly so that they present, successively, transversely alined pairs of pockets 42 accessible through the mouths 21 and 22 of the housing units 17 and 18.

At 59, I have generally indicated slats, each of which includes axially alined spindles 60 and 61. The length of the slats is substantially equal to the distance between the housing units 17 and 18. In practice, the slats 59 consist of a center part 62 and a pair of ends 63 and 64 slidably supported thereon so that the slats may be extended or shortened depending on the width of the particu-

ular window with which they are to be used (see Figs. 3 and 5). In practice, the spindles 60 and 61 are located somewhat nearer the edge portion 65 of each slat 59 than they are to its other edge portion 66 (see Fig. 3). The slats are preferably slightly reversely bent in cross section as will be apparent from Figs. 3 and 7. For reasons that will subsequently be apparent, each spindle 60 is substantially longer than the spindles 61 and include a U-shaped bend 67 establishing a crank disposed towards the slat edge 66.

From the foregoing, it will be apparent that a slat 59 may be slidably supported by the housing units 17 and 18 by inserting its spindles 60 and 61 into the mouths 21 and 22 respectively when band pockets 42 are in registry therewith. As the cross member 43 is pulled downwardly, the spindles are free to slide downwardly and inwardly along the downwardly and inwardly inclined slots 23 until they are seated in the inner extremity of the pockets 42 and in the vertical slots 19 and 20. In that position, the slat 59 moves upwardly and downwardly with the cross member 44 and may be removed therefrom by raising the cross member 43 until the open ends of the pockets 42 in which it is supported registers with the lower extremities of the inclined slots 23 upwardly along which the spindles may travel as the cross member 43 is raised further thereby to enable the spindles to be moved towards the open ends of the pockets 43 and through the mouths 21 and 22 of the housing units.

Referring now to Figs. 6 and 7, it will be noted that the end wall 35 of the upper portion 24 of the housing unit 17 blocks the vertical slot 19 of that unit so that a spindle 60 engaging therewith is cammed outwardly as the bands travel upwardly. While the other housing unit 18 may be similarly formed, such is not necessary, as I provide a magazine 68 for the slats 59. The magazine 68 may be supported as desired and, for convenience, I have shown each of its sides 69 as having a pair of upwardly inclined notches 70 disposed to engage with supporting screws 71 in the sides of the window casing 15 adjacent the transverse mount 16.

Secured to the interior surface of the sides 69 are a pair of transversely aligned arcuate channels 72 which receive the ends of the spindles 60 and 61. The magazine is dimensioned and the channels 72 are of sufficient length so that a sufficient number of slats 59 may be housed therein to complete the blind when each is slidably supported in the housing units. Latches 73 may be pivoted to bring their hook ends 74 into a position engaging the spindles 60 and 61 (see Fig. 10) to hold them against sliding under the influence of gravity downwardly along the channels 72 as when the magazine 68 is to be removed from the window casing 15. The channels 72 protrude a substantial distance beyond the sides 69 of the magazine 68 and are spaced to enter the mouths 21 and 22 of the housing units 17 and 18 adjacent the sides of the window casing 15 when the magazine 68 is secured thereto. The extremities 75 of the channels 72 extend into a position to intersect the path of spindles 60 and 61 of a slat 59 as it is raised to be engaged thereby and cam and guide the spindles 61 and 62 into their supporting channels as the cross member 43 is further raised.

When the cross member 43 has been pulled downwardly to seat adjacent the window sill and the spindles of a slat are supported by each pair of transversely aligned band pockets 42 in the vertically aligned slots 19 and 20 of the housing

units, the slats 59 are successively forced into the magazine 68 as the cross member 43 is raised to its uppermost position. By positioning the latches 73 to lock the spindles in the magazine, the magazine 68 may be detached from the window casing 15 and the slats 59 removed for washing or repair.

When the full magazine is again attached to the window casing 15 and the latches 73 positioned to release the slats 59 stored therein, the slats 59 are successively picked by the bands as pairs of pockets 42 are presented at the mouths 21 and 22 of the housing units as the cross member 43 is pulled downwardly.

In the preferred embodiment of my invention, I provide means to maintain the slats uniformly tilted and to enable all of these to be tilted simultaneously from one position to another so that the amount of light passing through my Venetian blind may be varied if desired.

To accomplish this result, I provide a spring wound drum in the housing 16 for the flexible band 77 which passes downwardly between the spacer blocks 36 and in parallel with the bands 38 and 39. The band 77 has its edge disposed towards the mouth 21 formed with a plurality of pockets 78, the upper and lower corners of each of which are rounded. As shown in the drawings, the band 77 is provided with a stop pin 79 engageable with one of the blocks 36 to prevent its passage upwardly therebetween.

The band 77 is connected to move with the bands 38 and 39 and to move vertically relative thereto between first and second positions. In the first position, each of the pockets 78 is spaced slightly above a pair of transversely aligned pair of pockets 42 and in the second position, shown in Figs. 6 and 7, each of the pockets 78 is slightly below that pair of pockets. When the slats 59 are disposed in the magazines 68 with their edge portions 66 lowermost, the pockets 78 are disposed in their second position to receive the crank portion 67 of a spindle 61 as the spindle 61 enters a pocket 42. When the slats 59 are supported by the pockets 42 and are slidably guided by the housing units, any slat may be tilted. When thus tilted, its crank portion 67 causes the band 77 to be raised with the result that all other slats 59 are uniformly tilted.

When the tilting band 77 is in its first position and the slats 59 are supported in their magazine as suggested in Figs. 6 and 10, the crank portion 67 of a slat at the mouths of the side units is blocked by the edge of the band 77 intermediate its pockets 78. Each crank portion 67 is, however, disposed closer to the slat edge 66 so that the slat 59 at the mouth of the side units is free to tilt with its spindle 60 entering the adjacent pocket and to turn to swing its crank portion 67 into the pocket 78. In that position, the slat 59 is tilted in a direction opposite to that shown in Fig. 7 thereby to expose its other face.

In practice, the band 77 may be regarded as connected to the other bands by means of the slat 59 adjacent the transverse member 43 which, for that reason, is not to be removed from the bands 38 and 39 under normal conditions and, for that reason, the uppermost position of the cross member 43 is preferably such that such lowermost slat is not cammed from the carrying bands 38 and 39.

To provide means for preventing the slats from being accidentally tilted from one position to another, I attach a leaf spring 80 to the extension 45 of the transverse member 43 which en-

gages the spindle 60 in the zone of its crank portion 67 to function as a brake.

In Fig. 11, I have shown the housing 37 for the carrying bands 38 and 39 with its cover 81 removed and in Fig. 12 I have shown a section through the housing with the cover 81 attached.

From Figs. 11 and 12, it will be noted that the housing 37 has a rotatable shaft 82 on which is mounted a drum 83 rotatable independently of the shaft having a chamber in each of its ends for the coiled springs 84 and 85 which are coiled in the same direction and have their inner ends secured to the shaft 82. The outer end of the spring 85 is anchored to the drum 83 to be tightened or released by rotating the drum 83 in one direction or the other and the other end of the spring 84 is secured to the cover 81 so that it may also be tightened by turning the cover as required to balance the weight of the slats 59. The bands 38 and 39 are intercoiled around the drum 83 with their inner ends suitably secured thereto. I provide the housing 37 with a separate port for each of the bands 38 and 39 with each port having a lip 87 to ensure that the bands do not catch as they enter or leave the housing 37.

Where relatively high windows are to be equipped with Venetian blinds in accordance with my invention, I may use the spring wound drum shown in Fig. 13, the housing 88 of which is generally similar to the housing 37. The housing 88 has a shaft 89 on which the drum 90 is mounted for rotation independently thereof. The drum 90 has a chamber accessible where the cover 91 is removed and to the shaft I mount a freely rotatable spacer 92 on opposite sides of which are collars 93 and 94 which are also free on the shaft 89.

Within the annular recess, I mount four springs 95, 96, 97, and 98, with the springs 95 and 98 being coiled in a direction opposite to the springs 96 and 97. The spring 95 has its outer end secured to the drum 90 and its inner end attached to the collar 93 to which the inner end of the spring 96 is also connected. The outer end of the spring 96 is connected to the spacer 92 to the other side of which is secured the outer end of the spring 97. The inner ends of the springs 97 and 98 are interconnected by the collar 94 and the outer end of the spring 98 is anchored to the cover 91.

By this construction, I am thus able to provide a spring that is relatively long for the diameter of the drum and at the same time enable a predetermined tension to be established by turning the cover 91 before attaching it to the housing 88. It will be apparent that the springs 84 and 85 of Figs. 11 and 12 may each be made in two sections if desired.

In Fig. 14, I have shown the housing 76 for the tilting band 77. This housing is similar to the housing 36 and in it I mount a drum 99 which is substantially identical to the drum 83 and is free to rotate on the shaft 100. Within the drum chambers, I mount springs 101 and 102 which are coiled oppositely to each other to ensure the proper operation of the tilting band 77. The inner ends of the springs 101 and 102 are anchored to the shaft 101 and their outer ends are connected respectively to the drum 99 and to the removable housing cover 103.

From the foregoing, it will be apparent that venetian blinds in accordance with my invention combine ease of operation with improved appearance and increased convenience both in use and in operation.

What I therefore claim and desire to secure by Letters Patent is:

1. A Venetian blind to be secured to a window casing, said blind comprising a pair of members mounted adjacent the sides of the window casing for vertical movement, said members having a plurality of pockets opening in the same direction transversely of the direction of travel of the members, a plurality of slats each of which is dimensioned to fit between said members and includes spindles to enter and be supported by a pair of pockets, means adjacent the upper part of said casing to transfer the spindles of each slat into or out of a pair of pockets as said members are raised or lowered in predetermined relation to said means, and guide means slidably guiding said spindles when seated in said pockets below said transfer means said transfer means intersecting the path of said guided spindles.

2. A Venetian blind to be secured to a window casing, said blind comprising a pair of members mounted adjacent the sides of the window casing for vertical movement, said members having a plurality of transversely aligned pairs of pockets opening in the same direction transversely of the direction of travel of the members, a plurality of slats each of which is dimensioned to fit between said members and includes axially aligned spindles to enter and be supported by a pair of pockets, guide means slidably guiding said spindles along a vertical path when supported by said pockets and a detachable magazine for said slats, said magazine including a pair of channel members disposed to receive the extremities of the spindles of the slats and extending outwardly and downwardly therefrom to intersect the path of such extremities at the upper end of said guide means thereby to transfer the spindles of each slat out of and into said magazine and into or out of a pair of pockets as said members are lowered or raised.

3. A Venetian blind to be secured to a window casing, said blind comprising a pair of members mounted adjacent the sides of the window casing for vertical movement, a third vertically movable member transversely aligned with said pair of members and located adjacent one of them, said members having a plurality of pockets opening in the same direction transversely of the direction of their travel, said pair of members having their pockets disposed as transversely aligned pairs and said third member having each of its pockets spaced vertically from each transversely aligned pair of pockets, a plurality of slats each of which is dimensioned to fit between said pair of members and includes axially aligned spindles to enter and be rotatably supported by a pair of pockets, one spindle of each slat having a bend establishing a crank extending through the adjacent pocket of said third member so that as any slat is tilted said third member is moved to effect a like tilting of the other slats while connecting said third member for vertical movement with said pair of members, means adjacent the upper part of said casing to transfer the spindles of each slat into or out of its supporting pockets as said members are raised or lowered in predetermined relation to said means, and guide means slidably guiding said spindles when seated in said pockets below said transfer means.

4. A Venetian blind to be secured to a window or like casing, said blind comprising a pair of vertical housing units adjacent to and in parallel with the sides of said casing, said units having transversely aligned mouths in their exposed faces,

transversely alined vertical slots in their opposed faces, and transversely alined, downwardly and inwardly inclined slots effecting communication between said mouths and said vertical slots, a spring wound band extending downwardly into each unit in parallel with said opposed faces, each of said bands having a plurality of spaced pockets disposed towards the mouth of its housing and intersecting its vertical slot, a transverse member slidably guided by said vertical slots and interconnecting said bands with each pocket of one band being transversely alined with a pocket of the other band, and a plurality of slats, each of said slats being of a length to fit between said units and including alined spindles to be supported by said pockets and slidably guided by said vertical slots, a magazine for said slots, said magazine including a pair of downwardly disposed channels to receive the extremities of the spindles of each slot and of sufficient length to extend into said mouths, and means to transfer said spindles between channels and said vertical slots when said transverse member is lowered or raised to bring a pocket downwardly to receive them from said channels or upwardly to the lower extremity of said inclined slots.

5. A Venetian blind to be secured to a window or like casing, said blind comprising a pair of housing units to be secured to the sides of said casing, said units having transversely alined mouths in their exposed faces, transversely alined vertical slots in their opposed faces, and transversely alined downwardly and inwardly inclined slots effecting communication between said mouths and said vertical slots, a spring wound band extending downwardly into each unit in parallel with said opposed faces, each of said bands having a plurality of spaced pockets disposed towards the mouth of its housing and intersecting its vertical slot, a transverse member slidably guided by said vertical slots and interconnecting said bands with each pocket of one band being transversely alined with a pocket of the other band, and a plurality of slats, each of said slats being of a length to fit between said units and including alined spindles to be supported by said pockets and slidably guided by said vertical slots, said spindles being transferable between said mouths and said vertical slots along said inclined slots when said transverse member is lowered or raised to bring a pocket downwardly past each mouth or upwardly past the lower extremity of each inclined slot.

6. The Venetian blind of claim 5 and endless cable means interconnecting the ends of the transverse member to ensure the equal movement of the bands.

7. A Venetian blind to be secured to a window or like casing, said blind comprising a pair of vertical housing units adjacent to and in parallel with the sides of said casing, said units having transversely alined mouths in their exposed faces, transversely alined vertical slots in their opposed faces, and transversely alined, downwardly and inwardly inclined slots effecting communication between said mouths and said vertical slots, a spring wound band extending downwardly into each unit in parallel with said opposed faces, each of said bands having a plurality of spaced pockets disposed towards the mouth of its housing and intersecting its vertical slot, a transverse member slidably guided by said vertical slots and interconnecting said bands with each pocket of one band being transversely alined with a pocket of the other band, and a plurality of slats, each

of said slats being of a length to fit between said units and including alined spindles to be supported by said pockets and slidably guided by said vertical slots, a magazine for said slats, said magazine including a pair of downwardly disposed channels to receive the extremities of the spindles of each slot and of sufficient length to extend into said mouths, and means to transfer said spindles between channels and said vertical slots when said transverse member is lowered or raised to bring a pocket downwardly to receive them from said channels or upwardly to the lower extremity of said inclined slots.

8. A Venetian blind to be secured to a window or like casing, said blind comprising a pair of vertical housing units adjacent the sides of said casing, said units having transversely alined mouths in their exposed faces, transversely alined vertical slots in their opposed faces, and transversely alined downwardly and inwardly inclined slots effecting communication between said mouths and said vertical slots, a member extending downwardly into each unit in parallel with said opposed faces, each of said members having a plurality of spaced pockets disposed towards the mouth of its housing and intersecting its vertical slot, a transverse member slidably guided by said vertical slots and interconnecting said members with each pocket of one member being transversely alined with a pocket of the other member, and a plurality of slats, each of said slats being of a length to fit between said units and including alined spindles to be supported by said pockets and slidably guided by said vertical slots, and means to transfer said spindles between said mouths and said vertical slots along said inclined slots when said transverse member is lowered or raised to bring a pocket downwardly past each mouth or upwardly past the lower extremity of each inclined slot.

9. A Venetian blind to be secured to a window or like casing, said blind comprising a pair of vertical housing units adjacent the sides of said casing, said units having transversely alined mouths in their exposed faces, transversely alined vertical slots in their opposed faces, and transversely alined downwardly and inwardly inclined slots effecting communication between said mouths and said vertical slots, a spring wound band extending downwardly into each unit in parallel with said opposed faces, a third spring wound band extending downwardly into one of said units in parallel with the other bands, each of said bands having a plurality of spaced pockets disposed towards the mouth of its housing unit and intersecting its slot, a transverse member slidably guided by said vertical slots and interconnecting the first named bands to maintain each pocket of one of them transversely alined with a pocket of the other, means interconnecting said third and other bands so that it may move with them or relative thereto between a first position in which each of its pockets is slightly above a transversely alined pair of pockets and a second position in which each pocket is spaced slightly below such a pair of pockets, a plurality of slats, each of which is of a length to fit between said units and includes alined spindles to be slidably guided by said vertical slots and rotatably supported in a transversely alined pair of pockets and disposed adjacent one of its edges so that a thus supported slat has a position in which it is held by gravity, one spindle of each slat including a

crank portion disposed intermediate the axis of said spindles and the other slat edge so that it may be slid through said mouths in its normal position into said pockets in one inclined position when said band is in its second position or 5 partially rotated and slid into said pockets in an oppositely inclined position when said third band is in its first position, the tilting of any one slat from one position to the other tilted position causing its crank to move said third band to tilt the other slats correspondingly.

10. The Venetian blind of claim 9 in which the holding means comprises one of the slats located adjacent the transverse member and spring means carried by the transverse member 15 to yieldingly engage the spindles of that slot adjacent its crank portion to function as a brake to hold the slat when tilted out of its normal position.

11. The Venetian blind of claim 9 and a magazine connected to the casing adjacent the upper ends of the housing units and including a pair of channels to receive and support the extremities of each slat in its normal position and ex- 20

tending downwardly and outwardly through the mouths to intersect the path of spindles seated in pockets and slidably guided by the vertical slots.

ROBERT H. SWACKHAMER.
